UNITED STATES PATENT OFFICE.

FRANK PERCY RUDDER, OF DERBY, ENGLAND.

FURNACE FOR REFUSE-DESTRUCTORS.

973,386.

Specification of Letters Patent. Patented Oct. 18, 1910.

Application filed July 29, 1907. Serial No. 388,098.

To all whom it may concern:

Be it known that I, FRANK PERCY RUDDER, British subject, and resident of Derby, county of Derby, England, have invented 5 certain new and useful Improvements in Furnaces for Refuse-Destructors, of which the following is a specification.

This invention relates primarily to the furnaces of refuse destructors and is designed to provide improved means for drying refuse garbage or other matter preferably before it is passed to the bright portion of the fire.

It consists essentially in conducting a portion of the hot gases from the combustion chamber or from some point beyond same into the whole or a part of the ashpit or the walls of the furnace and passing same either separately or mixed with air through the 15 whole or a part of the refuse in the furnace for a whole or a part of the period before or during combustion.

The invention will be fully described with reference to the accompanying drawings.

25 Figure 1 is a transverse section through a destructor furnace constructed according to one form of the invention. Fig. 2 is a section on line α — α , Fig. 1. Fig. 3 is a transverse section through a destructor furnace constructed according to a modified form of the invention. Fig. 4 is a section on line y — y , Fig. 3, parts being broken away. Fig. 5 is a section showing another modification. Fig. 6 is a longitudinal section showing further modification. Fig. 7 is a sectional plan of same.

In the simplest form of the invention shown in Figs. 1 and 2, a duct A communicating with the combustion chamber B is arranged behind the ashpits C and communicating with them through ducts D provided with dampers D'. One or more steam or compressed air jets E or other device to create a current are mounted between the 40 combustion chamber B or some point beyond it and the duct A, to direct the hot gases into the duct A and to one or all of the ashpits C communicating therewith. One jet or blower may be employed in the duct A or separate jets or blowers may be employed for each furnace and the dampers D' may then be dispensed with. The hot gases may be passed into the ashpit continuously and mix with the air entering same or they may 45 be passed into the ashpit only when a new charge has been inserted into the furnace, in

which case the air supply may be shut off for a time if desired. In another form of the invention, see Figs. 3 and 4, the ashpit C may be divided into two portions J K; a 60 main portion J into which the ordinary air supply passes and above which are arranged the ordinary fire bars F, and a second portion K in front of the charging door G and above which are arranged perforated plates 65 H, onto which the moist or wet refuse or other matter is first charged. Instead of the perforated plate H, bars, fire brick blocks, or other suitable table may be employed to receive the wet refuse. The second 70 portion K of the ashpit under the perforated plates H is divided into two portions, a lower portion which forms the duct A connected with the combustion chamber B, and an upper portion k' which is preferably divided into sections corresponding with the 75 separate furnaces or cells. The upper portions k' are divided from the hot gas duct A by a partition k² having dampers D² so that the hot gases pass into one or more of 80 the furnaces as desired. As before, a steam or other jet E or the like may be employed to draw or force the hot gases into the duct A.

Another form of the invention applicable to furnaces fed through the top is shown 85 in Fig. 5. This form is similar to that shown in Figs. 3 and 4 with the exception that the refuse or other matter is fed onto a dead plate L or the like and a perforated plate H' is arranged approximately vertically behind same so that the hot gases are forced through the charge from behind. When a new charge is inserted into a furnace it is placed on the perforated plate or the like H or the dead plate L; the hot gas 90 damper D² is opened and the hot gases from the combustion chamber B pass through the plate H and the new wet or damp charge, and quickly drive off all moisture, after which it is pushed forward onto 100 the bright fire upon the fire bars F and burned without cooling or damping the fire in any way. Or if desired the dried matter may be withdrawn without being burned.

Another form of the invention shown in 105 Figs. 6 and 7 combines in principle the form shown in Figs. 1 and 2 and Fig. 5.

In Figs. 1 and 2 the hot gases are passed into the undivided ashpit and rise through the whole charge on the grate. In Figs. 3 110 and 4, and also in Fig. 5, the ashpit is divided and the hot gases pass through only part

of the charge on the grate, namely, that part which rests on the perforated plate H, Fig. 3, or against the perforated walls H', Fig. 5.

- 5 In the destructor shown in Figs. 6 and 7 the combustion chamber B is arranged at the back of the grates and instead of a single duct therefrom for the hot gases common to all the grates, separate ducts A are 10 made in the walls between the grates which lead directly to the sides of the furnaces, separate blowers E being employed for each duct.

The furnace may be charged either from 15 the top or from the front, and when charged is filled up almost to the top. The hot gases are then passed through the charge and as the moisture is dried out of it, its bulk is greatly reduced and it gradually sinks down 20 and is burned up.

When the combustion chamber is not arranged behind the furnaces as shown, the ducts A in the walls may be arranged as 25 branches from a common duct in a manner somewhat similar to that already described.

From what has hereinbefore been stated, it will be clear that I provide a chamber for the drying and incineration of refuse. This chamber is what might be considered a 30 main or primary chamber, it comprising in the present case several distinct portions each denoted by the character C, and in these portions the material is capable of separate treatment. For example, while 35 the material in one of said portions is being subjected to incineration or burning the ash or residual in another of said portions can be withdrawn or otherwise disposed of, while, in still another, the material can be 40 dried. However, the invention is not limited in its embodiment to any particular number of portions in such a main or primary combustion chamber. In the form of embodiment illustrated, I provide in addition 45 to this main or primary combustion chamber, a secondary or auxiliary combustion chamber as B and I have represented a duct as leading from this auxiliary or secondary combustion chamber. This duct, 50 therefore, is in position to receive products of combustion from the main combustion chamber by way of the auxiliary combustion chamber, and I provide means for forcing 55 these products of combustion through the mass in the main combustion chamber in which the drying and incineration of the refuse take place.

The foregoing description applies particularly to the form of embodiment of invention shown in Figs. 1 and 2 especially, and is one way of carrying my invention into effect. The invention, however, does not reside in any specific construction, but broadly in a refuse burner having a chamber to contain refuse for incineration, means

for receiving products of combustion from said chamber, and means for forcing said products of combustion through refuse supported in said chamber. The products of combustion thus forced through the mass of 70 refuse effectually and thoroughly dry the mass and act as a vehicle for carrying off the moisture contained in said mass to the maximum heat zone of the combustion chamber and reach every particle or portion of the 75 mass and thereby avoid the labor of stoking or subjection of the mass to agitation.

In addition to the foregoing, what I have designated as the main combustion chamber or any one of the separate refuse receiving 80 portions may have and as shown in Figs. 3 and 5, for example, what might be termed a refuse drying part and a refuse combustion part to successively receive the refuse. The refuse drying part may be equipped with a 85 grate against which the refuse lies, and this grate may have one or a plurality of openings. In using a device of this type the refuse is first placed in the refuse drying part and dried, and after having been dried it is 90 moved to the refuse combustion part for combustion or incineration. In this form of the device I take a part of the products of combustion from the combustion chamber or at any other suitable point and force them 95 through the opening in the refuse drying part and also in the mass therein, and this opening in the present case will be that presented between the two bars of said grate.

The main body of the products of combustion pass through the chamber B, and then under or around a boiler if the apparatus is applied in such manner as to coöperate with a boiler and if there is sufficient heat in the gases for raising steam, and after traversing 100 the path just mentioned the said products of combustion then pass away to a suitable smoke duct or passage. Generally, only a small portion of the hot gases is forced by the blower back to the fires, the main portion 105 escaping to the duct or passage as above indicated, this escape to the duct or passage occurring directly when the products of combustion are not used for heating a boiler. The circulation of the currents including the products of combustion is indicated by the arrows in the several figures of the drawings.

What I claim is:

1. A refuse burner having a chamber for 110 the drying and incineration of refuse, means for receiving a portion of the products of combustion passing from said chamber, and means for forcing said products of combustion through the mass in said chamber to 115 dry the same.

2. A refuse burner having a chamber the bottom of which has openings through it, said bottom being adapted to support a mass of refuse for drying and incineration, means 120

for receiving products of combustion passing from said chamber, and means for forcing said products of combustion through the openings in said bottom and through the 5 refuse supported thereby.

3. A refuse burner having a chamber provided with a refuse drying part having an opening and also provided with a refuse combustion part, said parts being adapted 0 to successively receive the refuse, means for receiving products of combustion from said chamber, and means for forcing said products of combustion through said opening and through the mass in said refuse drying 5 part.

4. A refuse burner having a chamber provided with a refuse drying part and a refuse combustion part to successively receive the refuse, the refuse drying part having openings for passage therethrough of the refuse drying agent, a duct in communication with and adapted to receive the products of combustion which constitute the drying agent from said combustion chamber, and means 5 for causing the refuse drying agent to pass through said openings under pressure to act as a drying means upon the mass of refuse while in said drying part and for subsequently liberating the said agent.

5. A refuse burner having a combustion chamber provided with several distinct portions each to receive a body of refuse for incineration, each portion serving as an incinerating chamber or as a drying chamber, 35 means for receiving a part of the products of combustion from said combustion chamber, and means for forcing said products of combustion through the several portions of the combustion chamber whereby as the op-

eration of drying is taking place in some 40 of the distinct portions through the instrumentality of the products of combustion returned from the combustion chamber and passed through the wet refuse, incineration of the dried refuse is taking place in the 45 other distinct portions of the combustion chamber.

6. A refuse burner having a combustion chamber provided with several distinct portions each to receive a body of refuse for 50 drying and incineration, a duct for receiving products of combustion from said combustion chamber, means for forcing said products of combustion through the material in said several portions of said combustion 55 chamber, and means operable at will for arresting the passage of said products of combustion through any one of said several portions.

7. A refuse burner having a chamber provided with a refuse drying part and a refuse combustion part to successively receive the refuse, a duct in communication with said chamber and also in communication with said refuse drying part, and means for withdrawing products of combustion from said combustion chamber and forcing them through said duct for passage therefrom through the refuse in said refuse drying part.

In witness whereof, I have hereunto signed my name in the presence of two subscribing witnesses.

FRANK PERCY RUDDER.
